UNITED STATES PATENT OFFICE.

WILLIAM A. PECK AND JAMES M. MALONE, OF NEW HAVEN, CONNECTICUT; SAID
MALONE ASSIGNOR TO SAID PECK.

BOARD-TONGUE CUTTER.

Application filed May 16, 1925. Serial No. 30,831.

To all whom it may concern:

Be it known that we, WILLIAM A. PECK and JAMES M. MALONE, citizens of the United States, residing at New Haven, in the county of New Haven and State of Connecticut, have invented certain new and useful Improvements in Board-Tongue Cutters, of which the following is a specification, reference being had to the accompanying drawings.

This invention relates to tools, and particularly to a tool designed for the purpose of cutting or splitting off the tongue in matched flooring or sheathing.

It is often necessary in repairing buildings, putting in electric wiring, plumbing, etc., that the matched flooring be taken up, and in order to do this it is necessary to cut or split off the tongue of one board so as to permit this board to be lifted. The ordinary way of accomplishing this end is to drive a chisel down between the boards, thus splitting off the tongue so that the tongue remains within the one board and repeating the same operation on the other edge of the board.

The object of the present invention is to provide a tool which is especially adapted for this purpose and which will readily cut or split off the tongue without, however, making any large gap between the two boards, and further to provide a tool of this character which may be readily removed and readily put into operation.

A further object is to provide a tool which is so simple that it may be very cheaply made and which is so constructed that there is no danger of the knife being injured by coming in contact with nails used in holding down the sub-flooring, and in this connection to provide a tool having a horizontal shank portion within which the blade is disposed, the blade having a uniform width throughout its length and projecting beyond this shank portion only sufficient to split a flooring tongue without going into the sub-flooring, the shank acting as a stop preventing the too great driving in of the blade.

A further object is to provide a device of this character wherein the knife of the blade is removable and replaceable.

Other objects will appear in the course of the following description.

Our invention is illustrated in the accompanying drawing, wherein:

Figure 1 is a side elevation of the tongue splitting tool;

Figure 2 is a section on the line 2-2 of Figure 1;

Figure 3 is a side elevation of the knife;

Figure 4 is an end elevation of the blade.

Referring to this drawing, it will be seen that 10 designates preferably a rod or bar of metal constituting a shank which is circular in cross section and which is angularly bent to provide a handle 11 and a horizontal portion 12 disposed on a lower level than the handle and connected to the handle by an angular portion 13. The horizontal portion 12 at its extremity remote from the handle is upwardly curved, as at 15. This horizontal portion 12 of the metallic rod is longitudinally slotted or kerfed, as at 16, and disposed within this slit or kerf which extends the full length of the horizontal portion of the bar is the blade 17. This blade may be either beveled upon one face or beveled upon opposite faces, and the blade is held in place within the kerf 16 by rivets, bolts or screws 18. The blade is preferably of thin steel of uniform gauge so that it will not injure the wood when driven in between the joints of a floor.

In the use of this device, the blade is disposed at the joint between two boards and hammer blows struck upon the upper face of the horizontal portion 12 will force the blade downward between the two boards, the blade cutting into the tongue at its base and tending to split the tongue from the board, on which it is formed. As the tongue is split or cut, the blade is shifted longitudinally. In order to remove the blade from the floor so as to permit it to be shifted, it is rocked upon the portion 15 which constitutes a fulcrum. When the blade becomes worn or injured in any manner it may be readily replaced by removing the rivets, screws or bolts 18 and slipping the blade out and slipping a new blade in. The blade 17 is preferably formed with two or more perforations for the passage of the screws or bolts 18 and one of these is preferably elongated to permit the ready assembly of the blade. The handle 11 is preferably knurled so that it may be readily grasped and the blade held in correct position.

It will be seen that this device is very simple that it may be readily used, and it is extremely effective for the purpose intended.

We claim:

- 5 1. A tongue splitting tool comprising a shank formed to provide a horizontal portion, an upwardly turned portion, and a horizontal handle portion, the horizontal portion having a longitudinally extending
- 10 knife blade attached thereto, the blade having a uniform width from end to end and the shank at its end opposite the handle being formed to provide a fulcrum projecting beyond the end of the knife.
- 15 2. A tool of the character described comprising a shank formed to provide a horizontal portion, the shank being upwardly turned and then longitudinally extended to form a handle, the shank at the end opposite the handle being upwardly turned to constitute a fulcrum, and a longitudinally extending knife carried by said horizontal portion of the shank and having a uniform width.
- 20 3. A tool of the character described having a shank formed to provide a horizontal

portion angularly bent at one end and then horizontally extended to form a handle, the horizontal portion of the shank being longitudinally slitted from end to end, and a blade disposed within said slit and detachably engaged with the shank, the shank at its end remote from the handle being extended beyond the blade and upwardly turned to constitute a fulcrum.

35 4. A tool of the character described comprising a shank formed to provide a horizontal portion, an upwardly turned portion and a horizontally extending handle, the shank beyond the first named horizontal portion being upwardly turned to constitute a fulcrum, the horizontal portion of the shank first described being longitudinally slitted from end to end, a blade disposed within said slit, and attaching members 40 passing through the walls of the slit and through the blade and holding the blade in place.

In testimony whereof we hereunto affix our signatures.

WILLIAM A. PECK.
JAMES M. MALONE.
